UNITED STATES PATENT OFFICE.

CURTIS L. CRUVER, OF CHICAGO, ILLINOIS.

DEVICE FOR KILLING INSECTS.

1,110,312.

Specification of Letters Patent. Patented Sept. 15, 1914.

Application filed March 31, 1913. Serial No. 757,775.

To all whom it may concern:

Be it known that I, CURTIS L. CRUVER, a citizen of the United States, residing at Chicago, in the county of Cook and State of Illinois, have invented certain new and useful Improvements in Devices for Killing Insects, of which the following is a specification.

The object of this invention is to produce an improved device for killing insects, and particularly house flies, such a device being popularly known as a "fly-swatter."

In the accompanying drawings, Figure 1 is an elevation of a device embodying the features of my invention. Figs. 2 and 3 are enlarged sections on lines 2 and 3, respectively, of Fig. 1.

The device comprises a flexible member 5 preferably formed of wire screening, the edges of which screening may, if desired, be bound with cloth 6 or other suitable material. The lower end of the flexible member 5 is secured in a base 7 which comprises an integral piece of sheet metal folded along its longitudinal median line to form two sides 8 and 9, the side 9 being longer than the side 8. The ends of side 9 are rolled to form barrels 10 for the reception of arms on the handle. The handle 11 preferably is formed of wire suitably shaped to provide two arms 12 which lie in the barrels 10. Preferably the ends 8^a of the side 8 and the edges of the screen 5 extend into or adjacent to the barrels 10, and the arms 12 bear against the said ends 8^a. The barrels 10 and adjacent parts are compressed to secure the arms 12 therein, and also to clamp the ends 8^a against the binding 6 and the edges of the screen 5, so as to securely fix said screen in the base. The screen is also held in place by reason of the pressure exerted thereon by the sides 8 and 9. It will be noted that the barrels 10 perform the double function of securing the arms 12 to the base and of preventing the sides 8 and 9 of the base from spreading apart to release the flexible member 5.

On account of the simplicity of construction, the device may be manufactured very

cheaply, and it is therefore well adapted for use by mercantile houses as a souv-nir gift and an advertising medium. The face of the base 7 provides a convenient and desirable place for printing advertising matter.

I claim as my invention:

1. A fly swatter comprising a flexible member, a sheet metal base having two side portions between which one end of said member is held, said base having barrels at opposite ends, and a handle having a pair of arms extending into and rigidly clamped in said barrels.

2. A fly swatter comprising a flexible member, a sheet metal base having two sides between which one end of said member lies, and a handle having two arms, said base having barrels at its ends to receive said arms, said barrels acting to secure the handle to the base and further acting to clamp said flexible member to the base.

3. A fly swatter comprising a flexible member, a sheet metal base having two sides between which one end of said member lies, one of said sides being longer than the other and the former having barrels at its ends, a handle having two arms lying in said barrels, said arms bearing against the ends of the shorter side of the base, and said barrels and ends being compressed to clamp the edges of said flexible member and said arms tightly to the base.

4. A fly swatter comprising a sheet of wire screening, a binding at the edges of said screening, a sheet metal base folded to provide two sides between which one end of said screening lies, one of said sides being longer than the other and the former having integral barrels at its opposite ends, a wire handle having two arms lying in said barrels, said arms bearing against the ends of the shorter side of said base, and said barrels and adjacent parts being compressed to clamp said arms and the edges of the said screening to securely fix all the parts together.

5. A fly swatter comprising a flexible member, an integral sheet metal base providing two sides between which one end of

said member is held, a handle having a pair of arms extending at an angle to the base and lying at opposite ends of said base, and a single means at each end of the base for engaging said arms to secure them to said base and for preventing said sides from spreading apart

In testimony whereof I affix my signature in the presence of two witnesses.

CURTIS L. CRUVER.
